DIVING BOARD

Filed June 7, 1926

INVENTOR
W. S. BROWN

BY *Memorandum*

ATTORNEYS

UNITED STATES PATENT OFFICE.

WALTER STERRY BROWN, OF URBANA, ILLINOIS.

DIVING BOARD.

Application filed June 7, 1926. Serial No. 114,328.

My invention relates to improvements in diving boards, and it consists in the combinations, constructions, and arrangements herein described and claimed.

5 An object of my invention is to provide an improvement over my Patent No. 1,579,510, issued April 6, 1926. The improvement consists in providing a device in which the board proper is removable and reversible, 10 the fulcrum moved more readily, and which is more durable and efficient for the purpose intended.

A further object of my invention is to provide a diving board of the character 15 described in which that portion of the board behind the fulcrum flexes so as to lend a high degree of resilience thereto without undue strain on that portion above the fulcrum. It should be noted at the present 20 time that the ordinary type of spring board which flexes in front of the fulcrum and between the fulcrum and the diver frequently breaks at a point immediately over the fulcrum. My improved diving board 25 entirely eliminates this disadvantage.

A further object of my invention is to provide a diving board of the character described which possesses a higher degree of resiliency, and which imparts greater force 30 through a shorter distance to the diver than the ordinary type of diving board which overhangs the fulcrum for the major portion of the board.

A further object of my invention is to 35 provide a diving board of the character described in which the board proper may be reversed.

Other objects and advantages will appear in the following specification, and the 40 novel features of the invention will be particularly pointed out in the appended claims.

My invention is illustrated in the accompanying drawings, forming part of this application, in which

45 Figure 1 is a plan view of the board proper,

Figure 2 is a side elevation of the device, as applied to a pier,

50 Figure 3 is a plan view of the framework of the device,

Figure 4 is a plan view of a modified form of the framework, and

Figure 5 is a side elevation of the structure shown in Figure 4.

55 In carrying out my invention, I make use of a supporting surface 1, such as a pier, a

tank wall, or the like. My diving board consists of a member A which is formed of five wooden two-by-fours 2 placed parallel with one another and at a short distance 60 apart and substantially fourteen and one-half feet in length. These two-by-fours are secured to one another by cleats 3 and blocks 4 disposed transverse to the members 2. A frame 5 is provided having an enlarged end 6 and a plurality of relatively small openings 7 in the sides thereof. A crossbar 8 is disposed horizontally upon the sides of the frame 5, and is provided with threaded bolts at each end thereof which extend through 70 openings in the end 6, and is adjustably held in place by means of nuts 9.

A fulcrum 10 is rigidly secured to a fastening member 11. The fastening member 11 is provided with an opening in each end 75 thereof into which pins 12 are disposed. The pins 12 extend beneath the fastening member 11 and are adapted to be received in the openings 7 in the frame 5. The frame 5 may be secured to the support 1 by any 80 suitable means, such as bolts 13.

From the foregoing description of the various parts of the device, the operation thereof may be readily understood. The frame 5 is secured to the support 1, as shown in 85 Figure 2. The member A is disposed above the frame 5, one end thereof resting upon the crossbar 8, see Figure 2. A metal strip 14 is disposed upon the end of the member A adjacent the crossbar, and is provided with 90 outwardly extending integral lugs 15 which pass beneath the sides of the frame 5. In this manner, the end of the member A is held in place. The member A rests upon the fulcrum 10 at a point adjacent the forward 95 end thereof. It will be observed that the fulcrum may be moved rearwardly and held in place by disposing the pins 12 in the desired openings 7. This is illustrated by dotted lines in Figure 2.

In Figures 4 and 5, I have shown a modified form of frame which is substantially the same in construction as the frame 5, with the exception that the modified form is constructed mainly of metal pipes or tubes, and the frame 5 is constructed mainly of wood, such as two-by-fours. The modified form consists of sides 20 which are provided with relatively small openings 21 therein. A fulcrum 22 is disposed above the sides 20 and adapted to ride thereon. A fastening member 23, which is operatively con-

nected to the fulcrum 22, is provided with pins 24. The pins 24 are receivable in the openings 21, and in this manner, the fulcrum 22 may be secured in any desired position.

5 A crossbar 25 is adjustably secured to the frame, see Figure 4. A metallic strip 26, having outwardly extending integral flanges 27, is provided for holding one end of the member A adjacent the crossbar 25.

10 I claim:

1. A device of the character described comprising a frame, a crossbar adjustably carried by said frame, an elongated resilient member having one end disposed upon said crossbar, means disposed above said elongated resilient member and extending beneath said frame for holding the adjacent end of said member in close proximity to said crossbar, and a fulcrum adjustably disposed beneath said member and adjacent the forward end thereof.

2. A device of the character described comprising a frame, a crossbar adjustably carried by said frame, an elongated resilient member having either end adapted to be disposed upon said crossbar, one of said ends being disposed upon said crossbar, means disposed above said elongated resilient member and extending beneath said frame for holding the adjacent end of said member in close proximity to said crossbar, and a fulcrum adjustably disposed beneath said member and adjacent the forward end thereof.

3. A device of the character described comprising a frame, a resilient member having a block disposed at each end thereof, means carried by said frame for receiving one end of said resilient member, and holding means for holding said end and the block adjacent said end in place, said holding means being adapted to be moved whereby the held end of said resilient member may be freed, the resilient member reversed and the other end held in place by said holding means.

4. In a device of the type described, a frame, a resilient member, a block rigidly secured to one end of said resilient member, a crossbar, bolts extending through said cross bar and said frame, and means for receiving one end of said resilient member, said cross bar being adapted to engage with said block for holding said block and the end of said resilient member in place.

5. A device of the type described comprising a frame adapted to be secured to a support, said frame being positioned parallel with said support, a resilient member, means carried by one end of said frame for holding one end of said resilient member, a fulcrum disposed upon said frame beneath said resilient member, means for moving said fulcrum with respect to said frame and said resilient member, and means positioned between said frame and said resilient member for locking said fulcrum in adjusted position.

WALTER STERRY BROWN.
